UNITED STATES PATENT OFFICE.

THOMAS M. DANIELS, OF VALDEZ, DISTRICT OF ALASKA.

WATERPROOF FUSE-CAP.

No. 900,670.

Specification of Letters Patent.

Patented Oct. 6, 1908.

Application filed March 11, 1908. Serial No. 420,388.

To all whom it may concern:

Be it known that I, THOMAS M. DANIELS, a citizen of the United States, and a resident of Valdez, District of Alaska, have invented 5 a new and Improved Waterproof Fuse-Cap, of which the following is a full clear, and exact description.

This invention relates to fuse caps such as used for attaching an explosive cartridge to 10 the end of a fuse, which cartridge is to be used in blasting in mining.

The object of the invention is to produce a fuse cap of simple construction, which can be readily attached to the end of the fuse, 15 and which will be substantially water-tight.

The general purpose of the invention is to prevent the occurrence of "miss-fires" or "miss-holes" in blasting, which are due largely to the fact that the explosive in the 20 cartridge becomes wet. Such failures to explode are the direct cause of many mine accidents.

The invention consists in the construction and combination of parts to be more fully 25 described hereinafter and particularly set forth in the claims.

Reference is to be had to the accompanying drawings forming a part of this specification, in which similar characters of reference indicate corresponding parts in all the 30 figures.

Figure 1 is a side elevation of the end of a fuse having a fuse cap constructed according to my invention; Fig. 2 is a view similar to Fig. 1, but showing the inner end of the fuse cap broken away and shown in cross section; this view shows the fuse cap in the act of being applied to the fuse; Fig. 3 is a vertical section through a portion of the fuse 40 and the inner end of the cap, and showing the cap clamped to the fuse; Fig. 4 is an end view of the cap in its closed or clamped condition, the fuse being omitted; and Fig. 5 is a perspective showing a portion of the forward edge or inner end of the fuse cap, and showing especially the manner of forming the means for securing the cap to the fuse.

Referring more particularly to the parts, 1 represents the end of the fuse to which the 50 fuse cap 2 is attached. This cap consists of a tube or cylinder 3 closed at one end, and provided at its open end with a plurality of longitudinally disposed slits 4. The inner end of the cap, that is, the end having the 55 slits 4, is turned outwardly so as to form a crimp or crimped edge 5, as indicated most

clearly in Fig. 5. Before turning the edge in this manner, a part of the material of the crimped portion is struck inwardly so as to form a plurality of inwardly projecting 60 spurs or teeth 6. By reason of the slits 4 the inner end of the cap is formed into a plurality of sections or leaves 7, and these leaves are slightly bent outwardly so that by their own resiliency they tend to hold themselves in the outwardly inclined condition 65 illustrated in Fig. 2.

On the cap there is mounted a sliding ring or clamping ring 8. In applying the tube or shell 3 to a fuse, I slip over the end 70 of the fuse a sleeve 9, of rubber or similar material, which sleeve is considerably longer than the length of the slits 4, as indicated in Fig. 2. The cap containing the cartridge is then slipped over the end of the fuse with 75 the inner end of the fuse disposed at the sleeve 9. The clamping ring 8 is then forced to the inner end of the sleeve so that it presses the leaves 7 inwardly and clamps them against the sleeve 9. Forcing the leaves 80 7 inwardly in this manner presses the spurs 6 through the sleeve 9 and into the outer covering of the fuse 1. In this way the cap becomes firmly attached to the body of the 85 fuse.

A fuse constructed as described is substantially water-tight, as the sleeve 9 between the body of the fuse and the cap effectually prevents the passage of water to the interior of the cap or tube 3. The crimp 90 5 operates as a stop to limit the forward movement of the ring 8, and when the ring seats itself against this crimp, the tube or shell 3 will have become tightly attached to the fuse, as will be readily understood. 95

Having thus described my invention, I claim as new and desire to secure by Letters Patent:

1. A fuse cap having a cylindrical shell adapted to contain an explosive cartridge, 100 closed at one end and open at the other end, the open end having longitudinally disposed slits dividing the inner end of said shell into sections, and means for clamping said sections inwardly upon the end of the fuse 105 extending into said shell.

2. A fuse cap consisting of a cylindrical shell closed at one end and open at the other end, the open end having longitudinally disposed slits therein, and having spurs adapted to engage the sides of a fuse extending 110 in said shell, and a sliding ring on said shell

adapted to force said spurs inwardly to clamp said shell upon the fuse.

3. A fuse cap consisting of a shell having an open end and slits in the wall thereof extending longitudinally at said open end, a sliding ring on said shell adapted to clamp the slit portion of said shell upon the fuse passing into said shell, and a sleeve of waterproofing material disposed between said shell and the fuse and disposed under said slits, said sleeve affording means for excluding water from the interior of said shell.

4. A fuse cap consisting of a cylindrical shell having a split open end receiving the fuse, said open end having spurs formed thereupon projecting inwardly, a clamping ring sliding on said shell and adapted to clamp said spurs upon a fuse extending into

said shell, and a sleeve of waterproofing material adapted to surround the fuse and having a greater length than the split portion of said shell, whereby said sleeve excludes water from the interior of said shell. 20

5. A fuse cap having an open end with a crimped edge, said open end having longitudinal slits formed therein and spurs projecting inwardly, and a sliding sleeve on said shell adapted to force said spurs inwardly to clamp said cap upon the fuse. 25

In testimony whereof I have signed my name to this specification in the presence of two subscribing witnesses.

THOMAS M. DANIELS.
